UNITED STATES PATENT OFFICE.

WILLIAM P. WESTFIELD, OF PARK CITY, UTAH.

FIRE ESCAPE.

Application filed December 17, 1925. Serial No. 76,001.

The present invention relates to fire escapes.

The object of the present invention is to provide a structure that is convenient for the descent of women and children, said structure being movable to different windows so that persons occupying rooms contiguous to the apparatus may have free escape therefrom when interior outlets are cut off by flame and smoke.

Another object of the invention is to provide an apparatus of this character which may be moved along the building by persons on the ground, to a position adjacent to any of the windows.

A still further and important object is to so construct the apparatus that when not in use, it may be moved out of the way and does not interfere with the ordinary use of or view from the windows of the building to which it is applied.

The structure will be readily understood by reference to the accompanying drawings, wherein—

Figure 1 is a view in elevation of a building showing one form of the apparatus in place thereon and in operative position:

Figure 2 is a vertical sectional view through the same.

The same reference numerals are employed to designate similar parts throughout the several figures.

In the construction illustrated in Figs. 1 and 2, an ordinary flat faced building 10 is shown having the usual windows 11. Upon the front of this building are placed upper and lower spaced sets of rails 12 and 12¹ secured to the wall by suitable brackets, as 13. Intermediate rails 12² may also be employed if desired.

A set of stairs or steps are associated with these rails, said set of steps comprising side bars 16 connected by flat treads 17. A railing 9 is attached to the outer side bar and constitutes a banister to be grasped by persons ascending or descending the steps. The upper ends of the side bars carry brackets 14, upon the inner adjacent faces of which are journaled rollers 15, which run upon the upper rails 12. The lower end of the set of steps is preferably fitted on the outside of the lower rails 12¹ and has on the inner faces of the side bars 16 near their lower ends rollers 15¹, which rest upon the lower rails. Intermediate rollers 15², jour-

naled upon the side bars 16, bear upon the intermediate rails 12².

The distance between the upper rollers 15 and the lower rollers 15¹ is greater than the distance between the main portions of the tracks 12 and 12¹. Therefore, the steps will be held at an inclination and in convenient position so that women and children can descend the same. In order, however, that the steps will be well out of the way so as not to interfere with the windows under ordinary conditions, means are employed for suspending them vertically at the corners of the house. In the present instance, this is accomplished by raising one end of the upper set of rails, as shown at 12³, so that the distance between the rollers 15 and 15¹ will be substantially equal to the distance between the end 12³ of the upper set and the corresponding portion of the lower set of rails. At the opposite ends this same result is obtained by depressing the ends 12⁴ of the lower set, the result being that the steps can assume vertical positions at either corner of the building.

In order to operate the escape, cables 33 are employed, attached to the upper end of the set of steps and passing over pulleys 34 arranged contiguous to the ends of the upper rails, one of said pulleys being preferably located beneath the rail, the other being disposed above the same. The cables pass down to points convenient to be grasped by the firemen or other operators standing upon the ground.

If desired, the intermediate rails and rollers may be dispensed with, but when said intermediate rails are employed their opposite ends are respectively elevated and depressed as shown at 35 to permit the vertical hanging of the stairs.

It will be evident that this structure may be readily applied to any ordinary building and when not in use will not materially interfere with the ordinary employment of the windows. But if a fire should break out so that the interior exits were cut off, the stairs may be readily brought across any of the windows and will afford safe escape for the occupants of the building.

It will be understood that while the invention has been described in considerable detail, many changes and modifications may be made without departing from the scope of the invention.

Having thus described my invention, what I claim as new and desire to secure by Letters Patent, is:—

1. In a fire escape, the combination with a plurality of horizontal supporting rails, of a set of steps having rollers attached thereto in engagement with the said rails, the said rollers being attached to the said steps at greater distances apart than the perpendicular distance between the said rails whereby the said steps are held inclined to the said rails, and one of the said rails having a raised horizontal end portion whereby the steps may be raised from engagement

with the lower rail and suspended vertically. 15

2. In a fire escape, the combination with upper, intermediate and lower horizontal rails, of a supporting structure, a set of steps having rollers engaging all the said rails and, inclined transversely with respect to the said supporting structure, the upper and intermediate rails having horizontal raised portions to support the said set of steps in a vertical position whereby the rollers are raised from the lowest rail. 20 25

In testimony whereof I affix my signature.

WILLIAM P. WESTFIELD.
